UNITED STATES PATENT OFFICE.

ROBERT A. FORESMAN, OF CHICAGO, ILLINOIS, ASSIGNOR TO WESTINGHOUSE ELECTRIC & MANUFACTURING COMPANY, A CORPORATION OF PENNSYLVANIA.

UNDERFEED STOKER.

Application filed May 6, 1918. Serial No. 232,804.

To all whom it may concern:

Be it known that I, ROBERT A. FORESMAN, a citizen of the United States, and a resident of Chicago, in the county of Cook and State 5 of Illinois, have made a new and useful Invention in Underfeed Stokers, of which the following is a specification.

This invention relates to improvements in underfeed stokers and has for an object to 10 produce means for overcoming difficulties which have heretofore been encountered with such stokers.

In the drawings accompanying and forming a part hereof Fig. 1 is a fragmental perspective view of a well known type of underfeed stoker and illustrates the stoker equipped with an embodiment of my invention.

Fig. 2 is a perspective view of a section of 20 an air distributing box which forms a detail of the stoker illustrated in Fig. 1.

Fig. 3 is a perspective view of a fuel deflecting cap forming a detail of the present invention.

Fig. 4 is a fragmental longitudinal sectional view of a stoker illustrated in Fig. 1 and illustrates the fuel deflecting cap in place within the stoker. (The section is taken along a broken line so as to illustrate 30 the passage 9 and one of the caps 13 in section.)

Referring to Fig. 1; it will be apparent that the stoker there illustrated consists of alternately arranged fuel delivering retorts 35 5 and air supplying, fuel supporting portions 6, both of which extend from the front to the rear of the furnace. As illustrated, the retorts 5 are downwardly inclined toward the rear of the furnace and the 40 fuel supporting portions are similarly inclined and are made up of a plurality of separate twyer blocks 7. Each air supplying, fuel supporting portion 6, hereinafter for brevity and distinction in description 45 termed a fuel supporting surface, comprises a series of twyer blocks 7 located in overlapped and stepped relation. In addition to this, each twyer block is so formed that it, with an adjacent twyer block, forms a series 50 of air delivering passages which are adapted to deliver air into the retort across the normal line of movement of fuel from the retort and also to deliver air toward the rear of the furnace and in the general direction 55 of movement of the fuel through the

furnace. To accomplish this each twyer block is arched and is provided around its forward and lateral edge with a number of serrations or corrugations which form air delivery passages, between adjacent twyers, 60 and communicate with an air box located below the fuel supporting surfaces of the furnace. As shown in Fig. 1, the lateral walls 5^a of adjacent retorts are spaced so as to form an air delivery space 7^a which is in open communication with the air chamber below the fuel supporting surfaces. This space 7^a is bridged by the twyer blocks 7. 65

A fuel hopper 8 is shown located at the front of the furnace and communicating with each separate retort through a fuel delivery passage 9 which diverges, in a vertical plane, from its throat or narrower portion to its outlet within the combustion chamber of the furnace. In the stoker illustrated, fuel is fed from the hopper through the fuel delivery passage and into the furnace by means of a ram 10, which is adapted to be periodically reciprocated for this purpose. 70

From the above it will be apparent that the general direction of movement of the fuel from the hopper into the furnace is along the axes of the retorts. It will be understood, however, that in normal operation, 75 a fuel bed of considerable depth is maintained within the furnace and that the mouths of the fuel delivery passages 9 are located below the upper line of the fuel bed and that fuel is consequently fed into the 80 furnace below the combustion zone. In Fig. 4 of the drawings the irregular line approximately illustrates the upper level of the fuel bed. Under such operating conditions 85 it will be apparent that fuel fed into the retorts is gradually forced upwardly and out of the retorts by the incoming fuel, so that in general the retorts are filled with green coal and coal subjected to preliminary or 90 partial distillation by the sensible heat of the combustion taking place within the furnace. The crowding action of the incoming fuel causes the fuel within the retorts to be displaced laterally, or to be forced onto the fuel supporting surfaces 6 located between 95 the retorts. 100

Air is delivered to the upper portion of the fuel bed or to the combustion chamber above the fuel bed by means of an air box 11, which extends across the front of the 110

furnace and is located above the retorts and the fuel supporting surfaces 6. As shown in the drawings the air box 11 forms an air cooled portion of the front wall of the stoker and it also forms a part of the divergent 5 delivery portion of each of the fuel delivery passages 9. The air supplying openings 12 are, however, located above the passage 9 and are arranged so as to direct the flow of 10 air issuing from them into the upper portion of the fuel bed or into the space immediately above the fuel bed.

It is the common practice in multiple retort stoker construction to lock each series of 15 twyer blocks with an upper flat locking member. This locking member approximates in contour the external contour of the twyer blocks and forms a shelf on which the fuel entering from the delivery passage into 20 the retort may collect.

It has been found that some grades of fuel cause smoke to be discharged from the furnace through the fuel delivery passages into the boiler room. This difficulty 25 has been encountered with several types of underfeed stokers.

An object of my invention is to prevent smoke issuing from the furnace into the boiler room.

30 In accomplishing this object, I have eliminated the possibility of fuel collecting and remaining at the upper end of the fuel supporting surfaces. In other words, I have prevented fuel from collecting in pockets or on surfaces which are not in direct lines of travel of the fuel moving through the furnace by replacing the usual locking member with a fuel deflecting cap 13, illustrated in perspective in 35 Figure 3. This prevents fuel entering the furnace from being held in a more or less permanent position, where it is slowly coked by the heat of the furnace.

40 By employing a cap, such as is illustrated in Fig. 3, I have overcome the difficulty encountered with the old form of locking member, and I believe that this is due to the fact that the cap bridges the space between the uppermost twyer block and the front wall of the stoker, or as illustrated, 45 the space between the uppermost twyer block and the air box. In addition to this, the cap is of such contour that it will not only prevent fuel from lodging on it and being retained while subjected to a coking 50 temperature, but will also direct the fuel issuing from the passage 9 into a portion of the fuel bed where it is burned under satisfactory conditions of draft and fuel bed movement.

55 In addition to the above, I believe the fact that the caps form, in effect, extensions of the fuel delivery passages 9 also aids in overcoming the objectional phenomenon. 60 It may also be possible that the use of the

caps prevents the formation of objectionable air pockets or eddies within the fuel bed, and that it is therefore effective in aiding to direct the flow of air along proper lines of flow.

I am fully convinced, however, that any means which prevents fuel from lodging in pockets near the front of the furnace and also guides or directs the fuel into fuel bed, a portion subjected to a well defined rearward movement will, in a large measure, accomplish the desired results. For this reason I do not wish to limit myself to the structural details illustrated and hereinafter described.

80 As shown in Fig. 4 the cap 13 forms a locking member for the series of twyer blocks forming the fuel supporting surface of which the cap forms a part. In this respect it replaces and performs the function of the usual locking member. The forward and lateral faces of the cap are of such contour that they bridge the space between the innermost portion of the air box 11 and the uppermost twyer block 7, and are so formed that they present a surface on which fuel cannot lodge and be retained. In addition to this, each cap is provided with forwardly projecting ears 15 which engage a depending bracket 11^a of the air 90 box 11 and cooperate with the air box to form an extension of the adjacent fuel delivery passage 9. As shown in Fig. 4, the cap is provided with an interior chamber 16 which, like the twyer blocks, receives air 95 from the air space 7^a bridged by the twyer blocks and the cap. This air is delivered into the furnace through outlets provided between the lower face of the cap and the uppermost twyer block which outlets, as 100 illustrated, are formed by corrugations 17. Each cap is held in place by means of a bolt 18, which engages a portion of the 105 frame of the stoker. This bolt clamps the cap in place on the uppermost twyer block 110 and therefore locks all of the twyer blocks in place. This arrangement is similar to the arrangement usually employed in connection with locking members, now commonly in use, and a specific description of 115 the means employed for mounting the twyers is therefore not necessary.

110 While I have described and illustrated but one modification of my invention, it will be apparent to those skilled in the art 120 that various modifications, changes, additions and omissions may be made in the apparatus described and illustrated without departing from the spirit and scope of the invention as set forth by the appended 125 claims.

What I claim is:

1. In a furnace, in combination in an underfeed stoker, a downwardly inclined fuel feeding retort extending from the front wall 130

- of the furnace toward the rear of the stoker, a fuel supporting air delivering means located on each side of said retort, a fuel feeding hopper located at the front of the furnace and communicating with said retort, fuel feeding mechanism operating to force fuel from said hopper into said retort, a fuel guide member forming a cap for each fuel supporting air delivering means and a continuation of the fuel feeding passage between the hopper and the retort, said fuel guiding member having an exposed surface inclined forwardly and upwardly from the fuel supporting air delivering means to the effective front wall surface of the furnace at a greater angle of inclination than that of said fuel supporting air delivering means, whereby the lodgment of fuel and the formation of pockets at the upper end portions of the fuel supporting air delivering means are prevented.
2. In a furnace, in combination in an underfeed stoker, a downwardly inclined fuel retort extending from the front wall of the furnace toward the rear of the furnace, a fuel supporting air delivering means located on each side of said retort and extending downwardly from the front toward the rear of the furnace, a fuel delivery passage for delivering fuel from the front of the furnace into said retort and a fuel directing cap topping each fuel supporting air delivering means and forming a guide for fuel entering said passage, said fuel directing cap having an exposed surface extending forwardly and upwardly from the fuel supporting air delivering means to the effective front wall surface at a greater angle of inclination than that of said fuel supporting air delivering means, whereby the lodgment of fuel and the formation of pockets at the upper end portion of the fuel supporting air delivering means are prevented.
3. In a furnace, in combination in an underfeed stoker, a downwardly inclined fuel retort extending from the front wall of the furnace toward the rear of the stoker, a downwardly inclined fuel supporting air delivery means located on each side of said retort and comprising a series of over-lapping twyer blocks located in stepped relation and arranged to deliver air into said retort, a twyer locking member topping each series of twyer blocks and located at the front of said furnace and filling the space between the upper twyer block and the effective front wall of the furnace, said locking member having an exposed surface inclined forwardly and upwardly from the effective surface of the upper twyer block of each series to the front wall of the furnace at a greater angle of inclination than that of said series of twyer blocks.
4. In a furnace, an underfeed stoker comprising a fuel delivering retort extending from the front wall of the furnace toward the rear of the furnace, a fuel hopper located at the front of the furnace, and communicating through a fuel delivery passage with said retort, and a fuel supporting means located on each side of the said retort and extending downwardly from the front toward the rear of the furnace, the upper portion of each of the said fuel supporting means extending to the effective front wall of the furnace at an angle of inclination greater than that of the main fuel supporting means and forming a fuel deflecting extension of the said fuel delivery passage.
5. In a furnace, an underfeed stoker comprising a fuel retort extending from the front wall toward the rear of the furnace, a hopper communicating with said retort through a fuel delivery passage, an air distributing box located above the retort and extending across the front of the furnace transversely of said retort and a separate fuel supporting air delivery means located on each side of said retort and extending downwardly from the front toward the rear of the furnace, each of said fuel supporting air delivery means being topped by means bridging the space between the air box and the upper portion of the fuel supporting air delivery means at a greater angle of inclination than that of the fuel supporting air delivery means and forming a fuel deflecting extension of said fuel delivery passage.
6. In a furnace, the combination with an underfeed stoker having alternate fuel feeding retorts and series of fuel supporting twyers extending downwardly and rearwardly from the front wall of the furnace and having a transverse air box overhanging the front end of said retorts and twyers, of a fuel guide member mounted on the upper twyer of each series of twyers in close contact with the air box and having a surface sloping rearwardly from the effective air box surface to the twyers at a greater angle of inclination than that of the series of twyers.
7. In a furnace, the combination with an underfeed stoker having alternate fuel feeding retorts and series of fuel supporting twyers extending downwardly and rearwardly from the front wall of the furnace, and having a transverse air box overhanging the front ends of the said retorts and twyers, of a fuel guide member mounted on the upper twyer of each series of twyers in close contact with the air box and having a convex surface sloping radially from the effective air box surface to the twyers at a greater angle of inclination than that of the series of twyers.
8. In a furnace, the combination with a multiple retort underfeed stoker having alternate fuel feeding retorts and series of fuel supporting twyers extending down-

- wardly and rearwardly from the front wall of the furnace, of a fuel guide member mounted on the upper twyer of each series of tuyers at the point of joinder of the 5 tuyers with the front wall, said fuel guiding member having a surface sloping rearwardly from the effective front wall surface to the tuyers at a greater angle of inclination than that of the series of tuyers.
10. 9. In a furnace, the combination with an underfeed stoker having alternate fuel feeding retorts and series of tuyers inclined downwardly and rearwardly from the front wall of the furnace, of a twyer locking 15 block crowning the tuyers and serving as a fuel deflecting fillet at the point of joinder of each series of tuyers with the front wall, whereby fuel passing from the retort is directed into paths of fuel movement, the said 20 block having a rearwardly sloped exposed surface having a greater angle of inclination than that of the series of tuyers.
10. An article of manufacture for use in a furnace of the multiple retort underfeed type having alternate fuel-feeding retorts 25 and series of fuel-supporting tuyers extending downwardly and rearwardly from the front wall of the furnace consisting in a fuel-guiding, twyer-locking member having a bottom surface adapted to cooperate with 30 an upper surface of the uppermost twyer of a series, a forward surface adapted to conform to the effective front wall surface of the furnace and having a rearwardly inclined exposed surface having a greater angle 35 of inclination than the critical angle of repose of the fuel for which the stoker is adapted.
- In testimony whereof, I have hereunto subscribed my name this 2nd day of May, 40 1918.
- ROBERT A. FORESMAN.
